J. F. LAIRD.

Ore Stamp.

No. 11,229.

Patented July 4, 1854.

UNITED STATES PATENT OFFICE.

JOSEPH F. LAIRD, OF PHILADELPHIA, PENNSYLVANIA.

ORE-STAMPING MACHINE.

Specification of Letters Patent No. 11,229, dated July 4, 1854.

To all whom it may concern:

Be it known that I, Jos. F. LAIRD, of the city and county of Philadelphia and State of Pennsylvania, have invented a new and useful Improvement in Ore-Stamping Machines; and I do hereby declare that the following is a full, clear, and exact description of the same, reference being had to the accompanying drawings, making a part of this specification.

The advantage this invention has over that of Wm. Ball and others, is in the arrangement of the lifters operating on the adjustable weight affixed to the stamper rod, which in raising the stampers at the same time gives them a partial rotation, by an exceeding simple contrivance, viz., by so placing the lifters relatively to the head on the stamper rod, that they shall lay hold on the periphery of the head in the act of rising and thus turn the stampers; thus dispensing with grooves, catches, dogs, &c., heretofore required to render the operation effective; it must be a simple contrivance to make a practical one if it is considered the great weight of the head and stampers, and to make a good quartz crusher the stamper must be turned to prevent the undue wear of the face on the side where the rock is received in the mortar or bed; this irregularity of wear of the face of the stamper, it has been attempted to obviate by shifting by hand, and it is true that Ball has attempted this turning, but it is by a complex arrangement, which from slight causes have been found inoperative, whereas in my improved arrangement of the line or direction that the lifters assume on the axial line of the stamper head and its rod (by being placed on one side of the center of the head) the most perfect effect is produced, and the head and stamper allowed freedom of descent without friction or obstruction.

At first glance it may be supposed this does not differ from a rock drill to which a turning motion is given so as gradually to cut around the surface removed by it, but such an instrument is not used for the purpose this invention is designed to accomplish. The rock drill cuts away the surface by light taps and generally is turned by grooves on the under face of the head, or pawls, &c., while my machine cracks and breaks up the masses of rock by the weight of the stampers.

In the drawings A is the base of the machine on which the mortars are secured; B side sills; C a subsill for the mortars; D uprights rising from base A, united with a head piece and crosspiece, through which the rods of the lifters pass.

E is the mortar; F a tappet head through which the rods G pass; H, H the stampers, formed of simple cylinders with flat ends; I, I, I, three or more lifters on the shaft K; L the winch or handle, and M a case or cover in which the stampers rise and on the top of which the water used, is received and delivered to the stampers; a, a, a, series of projections on I, which coming in contact with the heads F upon one side of their center cause them partially to turn as they are lifted, simply by the adhesion of the lifters with the head.

The mode of using the crusher is as follows: The broken rock having been thrown in the mortar E at the hopper in the rear of the machine, a stream of water is turned on the top of the caphead M at the channel thereon; the stampers H being raised to different heights by the arrangement of the lifters I and, a a on the turning shaft K, there being always two out of three on the lift while the third one is relieved from the lifter and on its descent. This division of the labor, possesses the advantage of regulating the power applied without the intervention of a fly or balance wheel. The bed or mortar is of the usual construction and is furnished with the grate or strainer common to others.

The quartz rock having been received from the hopper and the stamper having made its first stroke upon the mass, on its rise through the agency of the rod G and tappet head F it is turned partially by the arms a a of the lifter and after its second descent a new portion of the face of the stamper is brought in contact with the bulk of the rock near the hopper, and thus being continually turned, is worn with a regular face until a portion of the length of the stamper being reduced the diminished length may be accommodated by sliding the rod G through the head F and secured by set screws.

Having thus fully set forth my improvement in machines for stamping quartz rock, what I claim as my invention, and desire to secure by Letters Patent, is—

The arrangement of the lifters, by being so placed as to operate on the periphery of the tappet head for the purpose of giving the stampers a partial rotation without requiring other mechanism, in the manner set forth.

In testimony whereof I have hereunto

signed my name before two subscribing witnesses.

JOSEPH F. LAIRD.
